UNITED STATES PATENT OFFICE.

WILLIE HOLDSWORTH, OF PROVIDENCE, RHODE ISLAND.

FALLER CAM FOR GILL-DRAWING FRAMES.

Application filed December 6, 1923. Serial No. 678,949.

To all whom it may concern:

Be it known that I, WILLIE HOLDSWORTH, a citizen of the United States, residing at Providence, in the county of Providence, 5 State of Rhode Island, have invented certain new and useful Improvements in Faller Cams for Gill-Drawing Frames, of which the following is a specification.

This invention relates to gill-drawing frames and consists of improvements in the faller-cams for the gill-screws.

One object of the invention is to provide a cam-member for the bottom-screw having unitary guiding-means embodied therein 15 which acts to guide the faller-bar in transferring it from the bottom-screw to the top-screw, whereby to insure the proper engagement of the bar with the threads of the top-screw.

Another object of the invention is to provide a guiding-means on the faller-cam which acts to guide the faller-bar during its complete movement of transfer from one screw to the other.

Another object of the invention is to provide a faller-cam having a guide-flange or fin adapted to pass through an opening or slot in the top-screw, which opening is made without mutilating or cutting away the 30 threads to weaken them at any point.

Another object of the invention is to provide guiding-means on the faller-cam adapted for use with a top-screw in which the screw-threads are left with sufficient stock 35 to reinforce them at their ends.

Another object of the invention is to provide guiding-means on the faller-cam which may be accommodated by cutting away the top-screw with a simple machining 40 operation without requiring filing or hand-fitting of the threads.

Another object of the invention is to provide a faller-cam for the gill-screw which may be constructed as a complete unit adapted 45 to be interchangeably applied thereto so that a broken cam may be replaced by a new one without machining or fitting the parts.

Another object of the invention is to provide a faller-cam of stronger construction and greater durability to resist the hard wear to which it is subjected in the machine.

Another object of the invention is to provide a faller-cam which may be attached to

the gill-screw without removing or dismantling the mechanism of the gill-drawing frame.

Further objects of the improvement are set forth in the following specification which describes a preferred embodiment of the invention as illustrated by the accompanying drawings. In the drawings:

Fig. 1 is a side elevation of the top-screw and bottom-screw of a gill-drawing frame showing my improved faller-cam as applied to use with the bottom-screw;

Fig. 2 is a fragmentary view of the top-screw and bottom-screw showing my improved cam in position on the bottom-screw and illustrating the manner in which the faller guiding-means passes through the cut-out portion of the top-screw;

Fig. 3 is an end view showing the relation of the two faller-cams on the bottom-screw and illustrating the manner in which they act to lift the faller-bars into engagement with the top-screw.

Fig. 4 is a similar view showing an earlier stage in the operation of transferring the faller-bar from the bottom-screw to the top-screw;

Fig. 5 is a fragmentary view of the top-screw and bottom-screw showing the faller-bar in section and illustrating it in position as it leaves the faller-cam during its traverse by the top-screw; and

Fig. 6 is a detailed perspective view of a preferred embodiment of my improved faller-cam.

Referring first to Fig. 1 of the drawings, I have here shown the top-screw 2 and bottom-screw 3 of a usual type of gill-drawing frame as journaled in end-bearings 4 and 5 and adapted to be rotated in opposite directions by means of suitable gearing at their ends, indicated by the reference-character 6. It will be understood that there are two sets of gill-screws arranged in opposite relation in the gill-drawing frame with the gill-bars or fallers extending therebetween and adapted to be traversed in opposite directions by engagement with the threads of the screws. The faller-bars 7 are constructed in the form of toothed combs which slide on horizontal supports or saddles, not herein shown, being traversed slowly in one direction by the top-screws 2 during their operative stroke,

and then returned in the opposite direction by the bottom-screws 3 at a faster speed. Suitable cam-members 8 at the ends of the top-screws 2 act on the gill-bars or fallers 7 to transfer them from the top-screws 2 to the bottom-screws 3 at the end of their traverse in one direction, and another set of cams 10 on the bottom-screws lift the bars at the completion of their return movement to engage them once more with the threads of the top-screws.

My present improvement relates more particularly to the faller-cams 10 for the bottom-screw, although it is to be noted that the improvement might be applied to the cams for the top-screw if desired. Heretofore in the present art it has been the practice in most instances to employ faller-cams without guiding-means and to mount vertical "conductors" or rigid faller-guides on the frame of the machine for guiding the faller-bars as they are transferred from the bottom-screws to the top-screws. In other cases, the fixed conductors or faller-guides have been eliminated by the use of disk-cams for the bottom-screws, such cams having a circular rim or disk for guiding the faller-bars in their transit from the bottom-to the top-screws, this construction of cam being described and illustrated in my U. S. Letters Patent No. 1,118,346, dated October 13, 1914. The use of a disk-cam such as described in the patent referred to is open to some objection, however, since the threads on the top-screw must be cut away at their ends to provide that the guiding-flange may intersect the top-screw at a point where the faller-bars enter into engagement with the threads. In fact, the threads of the top-screw must be very materially mutilated or cut away at their ends and finished down to a sharp point, as shown in the patent above referred to and also in my U. S. Letters Patent No. 1,329,904, dated February 3, 1920.

It will be noted by reference to Fig. 1 that the bottom-screw 3 has a reduced shank 11 and a body portion of larger diameter in which the threads 12 are cut. The threads of the bottom-screw are of double pitch, cut with a relatively long lead and with the grooves spaced at a relatively wide distance apart; while the upper-screw 2 has narrower threads of double pitch with less lead. It will also be noted that the threads on the bottom-screw are not cut clear through to the end of its enlarged portion, a substantial hub or solid butt 13 being left for reinforcement between the threads and the reduced shank 11. This butt end of the threaded portion of the screw is slotted longitudinally on its opposite sides to provide seats or recesses 14 in which the cam-members 10 are held.

Referring now particularly to Fig. 6, my

improved cam member comprises a rectangular foot or bar 15 adapted to fit into one of the slots 14 in the butt end or hub 13 of the screw and provided with holes 16 through which are inserted suitable bolts 17 for fastening the cam in place on the screw. Projecting radially outward from the foot 15 is an arm 18 formed at its end with a forwardly-projecting rounded protuberance or cam-nose 19 having a circular bearing-face 20 at its end. The outer peripheral edge of the cam 10 is formed concentric with the axis of the screw on which the cam is mounted and extending forwardly from the cam-nose 19 is a lateral flange or fin 21 which constitutes the guiding-means for the faller-bar as it rides on the rounded end 20 of the cam. The outer peripheral edge of the flange or fin 21 is extended circumferentially or concentric with the axis of the screw, as illustrated most clearly in Fig. 3, and its forward end is rounded off at 22 so that it assumes the shape of a finger projecting in advance of the curved face 20 of the cam 19. The forward end of the guide-flange 21 is pitched or inclined slightly to the left of the cam-nose 19, as viewed in Fig. 2, for a purpose as later explained. The rearward side of the cam-member 19 is beveled off at 23, leaving an inclined shoulder or ledge 24 which is, in effect, a continuation of the peripheral edge of the flange or finger 21, see Fig. 6. The beveled face 23 on the rearward side of the cam is designed to provide a clearance for the threads of the top-screw where the cam intersects the latter as shown in Fig. 5 and explained more fully hereinafter. It will be understood that there are two cams at the rearward end of the threaded portion of the bottom-screw 3 which are arranged in opposite diametrical relation with their foot-pieces 15 secured in the slots 14 in the butt or hub 13 of the screw.

Referring now to Figs. 1 and 2, the rearward end of the enlarged threaded portion of the top-screw 2 is formed with a butt or solid hub-portion 25 similar to the butt 13 on the bottom-screw 3. This serves as a reinforcement for the screw-threads at their ends and strengthens and stiffens the screw at a point midway between its bearings where formerly it was weakest. The cam-member 10 on the bottom-screw 3 intersects the top-screw 2 at this point and the butt or solid part of the screw provides for cutting away the metal without unduly weakening the screw. It will be noted from Figs. 1 and 2, that the guiding-flange or fin 21 is offset laterally from the upper face of the cam-nose or protuberance 19 and the top-screw 2 is cut away at 26 to provide a clearance for the flange. Stated briefly, instead of continuing the thread into the butt 25 in

a spiral or helix it is cut across at this point to form a relatively wide opening between the squared shoulder 27 and the next thread on the screw. At the same time the thread 5 still remains connected with the hub or butt 25 by a substantial thickness of metal which reinforces it from the butt. It will be noted that this cut or opening 26 in the screw is made with square edges so that it may be milled out or machined away without hand work such as filing or fitting. Where the end of the thread merges into the squared portion of the cut it is beveled off on its side at 28, but only to a slight extent, to provide a clearance for the beveled side 23 of the cam projection 19. It will be seen by reference to Fig. 5 that the bevel 23 on the side of the cam provides a clearance between the cam and the side of the thread on the 20 top-screw without narrowing the thread to any considerable extent where it merges into the butt or solid portion of the screw. As there are two cams on the bottom-screw 3 it is necessary of course to have two cut-out 25 portions at the end of the threads of the top-screw. Fig. 2 shows the fin or flange 21 on one of the cams entering the cut-out portion 26 on the top-screw and in this view the end of the cut on the opposite side of 30 the screw is shown at the top as designated at 29.

The method of operation of the two screws and the manner in which my improved faller-cam cooperates therewith will now be explained in detail: Referring to Fig. 1 of the drawings, it has before been explained that there are two sets of top-screws 2 and bottom-screws 3 between which the faller-bars 7 extend in horizontal relation with their 35 ends engaging the threads of the screws, but for the present purpose it will be sufficient to describe the action of the faller-cam of a single bottom-screw in shifting the faller therefrom to the top-screw. The faller-bars or combs 7 are supported by horizontal saddles which are not illustrated in the present drawings in order not to obscure the showing of the screws themselves. The top-screw 2 propels the faller-bars to the right as viewed in Fig. 1, and as they reach the end of the screw 2 the cam 8 comes into engagement with the top of the fallers to carry them down into the threads of the bottom-screw 3. During the transfer of the 40 faller-bar from the top-screw to the bottom-screw it is guided by the end plate or bearing 5, and as its end enters the thread groove in the bottom-screw it is traversed back to the left to be once more transferred to the top-screw. As the faller-bar reaches the rearward end of the thread groove in the bottom-screw 3 one of the cams 10 is brought around beneath it and, bearing at its rounded nose-end 19 on the bottom of the bar, it acts to

lift the latter as illustrated in Fig. 4. The 65 lifting action of the cam 10 on the bar 7 will cause the end of the bar to enter the end of one of the thread grooves on the top-screw 2, it being noted from Fig. 1 that the end of the faller is tapered off and slightly inclined from the vertical as indicated by the dotted lines so that it will conform to the helical edge of the threads on the screws. 70

Referring to Figs. 1, 2 and 4, it will be seen 75 that immediately the faller-cam 10 comes into engagement with the bottom edge of the faller-bar 7 its guiding-flange or fin 21 will ride up along the side of the bar to hold the latter from lateral displacement 80 and to direct its movement to properly engage its end with the thread groove in the top-screw 2. It has been explained that the flange 21 is slightly offset or inclined to the left at its end, as viewed in Figs. 1 and 2, and the purpose of this is to insure that the leading edge of the flange will clear the under edge of the bar so that the bar will be properly engaged by the side face of the flange. Now as the bottom-screw 3 continues 85 to rotate in the direction indicated by the arrows in Figs. 3 and 4 the faller-bar will ride off from the rounded end 20 of the cam-nose 19 and onto its peripheral edge as indicated in Fig. 3, Fig. 4 showing the engagement 90 of the cam with the bar during the first stage of the operation of lifting the bar. As the bar is released from engagement with the guiding-flange or fin 21 it enters into complete engagement with the threads of 95 the top-screw and the continued rotation of the bottom-screw carries the cam through the cut or opening 26 in the top-screw 2, as shown in Fig. 3. It will be observed from this view that the top-screw is not cut away to a depth greater than the depth of the threads in the screw or, in other words, the body of the screw remains unmarred so that the screw is not weakened at this point. As the faller-bar 7 enters into engagement 100 with the threads of the top-screw it is traversed to the right and eventually rides off from the outer peripheral edge of the cam 10 as illustrated in Fig. 5. As the faller leaves the cam 10 it meets the upper edge of the saddle, not herein shown, and is supported thereby during its traverse along the threads of the top-screw. As the two screws 105 continue to rotate the next faller-bar traversing the threads of the bottom-screw reaches the end of the thread groove and is engaged by the opposite cam 10 thereon whereby it is lifted into engagement with the top-screw in the same manner as previously explained. In this way as the faller-bars reach the inner end of the threads 115 of the bottom-screw they are each in turn lifted by one of the cams 10 and the guiding-flange 21 on the side of the cam-nose serves 120 125

as a support or retainer to prevent the bars from being displaced laterally. The bars will thus be effectually guided into proper engagement with the threads of the top-screw. In this connection it will be understood of course that the faller-bars will also be guided on their opposite sides by the ends of the saddles across which they ride in the manner as well known to those versed in the art.

It will be observed that my present improvement provides an especially simple and efficient guiding-means for the faller-bars which may be constructed as a part of the faller-cam at very little added expense to the cost of manufacturing the usual form of cam. My improvement provides for eliminating the extra conductors or rigid guides heretofore attached to a fixed part of the machine, and also obviates the use of the heavy cumbersome disk-cam which requires mutilation and weakening of the threads of the top-screw.

With the present improvement the cam and its guide-flange is constructed as a single unit and is therefore much lighter in weight and less cumbersome than the disk-cams previously employed. Moreover the present form of guiding-means on the cam is adapted to intersect the top-screw in such a way that the threads of the screw do not have to be filed down to a point and fitted by manual operations. The threads of the screw are therefore not mutilated or weakened and hence are less liable to be broken, so that the screw is made more durable under the hard use to which it is subjected in the machine.

My improved cam may be made to stand-
ardized dimensions so as to be interchangeable to replace broken or damaged cams without machining or refitting the parts. Furthermore, the cams can be set in place and attached to the screw without removing the latter from the machine and consequently provides for a considerable saving in time and labor in making repairs and replacements.

While I have herein disclosed a preferred form of the cam and its integral guiding-flange or fin, it is obvious that the form and structure of this part of the invention may be varied if desired, and therefore without limiting myself as to the exact embodiment shown, I claim:

1. In a gill-drawing frame, the combination with the top-screw and bottom-screw thereof, of a radial cam-arm on one of the screws provided with a guiding-flange offset laterally from the working-face of the cam and projecting therefrom in position to engage the side of the faller-bar to sup-

port and guide said bar as it is transferred from one screw to the other.

2. In a gill-drawing frame, the combination with the top-screw and bottom-screw thereof, of a faller-cam on one of the screws comprising a substantially radial arm formed with a forwardly projecting cam-nose, and provided with a laterally offset guiding-fin projecting in advance of the cam-nose to adapt it to engage the side of the faller-bar to guide the latter in its transit from one screw to the other.

3. In a gill-drawing frame, the combination with the top-screw and bottom-screw thereof, of a faller-cam having a foot held in a slot in one of the screws and provided with an arm extending substantially radially therefrom with a forwardly projecting cam-nose at its end, and a lateral guiding-flange extending circumferentially in advance of the working-face of the cam to adapt it to abut the side of the faller-bar as the latter is transferred from one screw to the other by the cam.

4. In a gill-drawing frame, the combination with the top-screw and bottom-screw thereof, of a faller-cam on the bottom-screw comprising an arm formed with a forwardly projecting cam-nose provided with a laterally offset guiding-flange the top-screw being cut away on its circumference without thinning the threads of the screw to provide an opening for the passage of the guiding-flange therethrough as the screws are oppositely rotated.

5. In a gill-drawing frame, the combination with the bottom-screw thereof, of a faller-cam on said screw comprising a radial arm formed with a forwardly projecting cam-nose having a lateral guiding-flange projecting circumferentially in advance thereof, and a top-screw having helical threads merging into a substantial hub or cylindrical reinforcing butt at their ends, said butt cut through on its circumference without materially reducing the cross-sectional area of the threads to provide an opening for the passage of the guiding-flange to adapt the cam to intersect the threads of the top-screw.

6. An improved faller-cam for gill-screws comprising a foot for attachment to the screw, and an arm extending from said foot and formed with a forwardly projecting cam-nose having a lateral guiding flange offset from its side and projecting in advance of its working face to adapt it to abut the side of the faller-bar as the latter rides on the cam.

In testimony whereof I affix my signature.

WILLIE HOLDSWORTH.
